UNITED STATES PATENT OFFICE.

ROBERT S. DRUMMOND, OF DETROIT, MICHIGAN, ASSIGNOR TO DETROIT STEEL PRODUCTS COMPANY, OF DETROIT, MICHIGAN, A CORPORATION OF MICHIGAN.

WEATHERING FOR METALLIC WINDOW-SASHES.

1,197,017.

Specification of Letters Patent. Patented Sept. 5, 1916.

Application filed July 22, 1915. Serial No. 41,223.

To all whom it may concern:

Be it known that I, ROBERT S. DRUMMOND, a citizen of the United States of America, residing at Detroit, in the county of Wayne and State of Michigan, have invented certain new and useful Improvements in Weathering for Metallic Window-Sashes, of which the following is a specification, reference being had therein to the accompanying drawings.

The invention relates to metallic window sashes and frames, and it is the object of the invention to provide more effective weathering for the joints.

In the present state of the art a common form of joint between sliding metallic window sashes and frames is formed by channel bars having the flanges of one fitting within those of the other. The weathering is effected by contact of the edges of the inner channel bar with the sides or bottom of the outer bar, but on account of the imperfect contact there is always more or less leakage of air. The reverse arrangement of the channels leaves a space therebetween, but this has not heretofore served any useful purpose. With the present invention I utilize this space for installing additional weathering, which greatly decreases the leakage of air between the sash and the frame. I have further discovered that by the arrangement of this weathering so as to form a tortuous course for the air to pass and one having a plurality of expansion chambers, the effectiveness is greatly increased.

In the drawings: Figure 1 is a cross section through a window sash and frame to which my improvement is applied; and Fig. 2 is a similar view showing a modified construction.

A is a metallic window sash having stiles formed of channel bar.

B is the window frame, which as shown is provided with a channel bar C fitting within the channel of the bar A, and having its flanges C' slightly flaring to contact at their edges with the sash.

Within the space formed by the engagement of the bars A and B, I place a weather strip D, preferably an angle bar, one flange of which is secured to the sash rail or stile, while the other flange extends into proximity to the bottom of the channel bar C. This latter flange is also preferably ar-

ranged substantially centrally between the flanges C' of the bar C so as to divide the space into two separate chambers E and E'.

With the construction as described, the air current from the outside of the sash which tends to force in around the edges of the flanges C' is intercepted by the flange D, and the change of direction which is compelled tends to form an eddy which further interferes with leakage. In the same manner such air as does pass about the flange D from the chamber E to the chamber E' is again compelled to change its direction and form an eddy within the chamber E' which further interferes with leakage. Thus practical tests have demonstrated that the weather-proof character of the joint is greatly improved by this additional weathering.

The construction shown in Fig. 2 is the same as that in Fig. 1, with the exception of additional flanges F and F' on the frame which embrace the flanges of the sash channel bar A. This will produce two more changes in direction with a corresponding improvement in the weather proofing.

What I claim as my invention is:

1. In a metallic window sash and frame construction, the combination of oppositely arranged channel bars respectively forming part of the sash and frame, the one fitting within the other, and additional weathering located in the space inclosed by said channel bars comprising means for dividing said space into a plurality of air expansion chambers separated by a restricted passage, said expansion chambers being relatively large as compared with said restricted passage.

2. In a metallic window sash and frame construction, the combination of oppositely arranged channel bars respectively forming part of the sash and frame, one fitting within the other to form restricted air passages, and additional weathering within the space inclosed by said bars comprising a flanged member secured to the bar having the outer flanges and extending into proximity to the bottom of the channel in the opposite bar, said flanged member with said channel bars forming separate air expansion chambers, of relatively large size as compared with said restricted passages.

3. In a metallic window sash and frame construction, the combination of oppositely arranged channel bars respectively forming

part of the sash and frame, one of said channel bars fitting within the other and having its flanges slightly flared and forming restricted air passages therewith, and additional weathering located in the space inclosed by said channel bars, comprising an angle bar having one flange secured to the channel bar, the flanges of which embrace those of the others, and the edge of said angle bar extending in proximity to the bottom of the opposite channel bar, said angle bar with said channel bars forming separate air expansion chambers, of relatively large size as compared with said restricted passages.

4. In a metallic window sash and frame construction, the combination with oppositely arranged channel bars each respec-

tively forming part of the sash and frame, the flanges of one embracing those of the other and forming therewith restricted air passages, of additional weathering located in the space inclosed by said bar comprising an angle bar secured to the web of the channel bar having the embracing flanges, the outwardly extending flange of said angle bar being arranged substantially centrally within the inclosed space and at a substantial distance from the embraced flanges of the channel bar to form air expansion chambers and extending into proximity to the bottom of the opposite channel, said expansion chambers being relatively large as compared with said restricted passage.

In testimony whereof I affix my signature. 3
ROBERT S. DRUMMOND.
